US00D996220S

(12) **United States Design Patent** (10) Patent No.: **US D996,220 S**
 Berlepsch et al. (45) Date of Patent: **** Aug. 22, 2023**

(54) **BOTTLE**

(71) Applicant: **The Procter & Gamble Company**,
 Cincinnati, OH (US)

(72) Inventors: **Joseph Allen Berlepsch**, Hamilton, OH
 (US); **Timothy Ling**, Cincinnati, OH
 (US); **Nolwenn Husson**, Geneva (CH);
Jan Wertel, Munich (DE); **Gernot
 Oberfell**, Munich (DE); **Markus Mau**,
 Munich (DE)

(73) Assignee: **The Procter & Gamble Company**,
 Cincinnati, OH (US)

(**) Term: **15 Years**

(21) Appl. No.: **29/770,510**

(22) Filed: **Feb. 12, 2021**

(30) **Foreign Application Priority Data**

Aug. 14, 2020 (WO) WIPO97057

(51) LOC (14) Cl. **09-01**

CLAIM

The ornamental design for a bottle or the like, as shown and described above.

DESCRIPTION

The file of this patent contains at least one drawing executed in color. Copies of this patent with color drawings will be provided by the office upon request and payment of the necessary fee.

FIG. 1 is a perspective view of a first embodiment of a bottle;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a bottle;

FIG. 9 is a front view thereof;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is a perspective view of a third embodiment of a bottle;

FIG. 16 is a front view thereof;

FIG. 17 is a back view thereof;

FIG. 18 is a left side view thereof;

FIG. 19 is a right side view thereof;

FIG. 20 is a top view thereof;

FIG. 21 is a bottom view thereof;

FIG. 22 is a perspective view of a fourth embodiment of a bottle;

FIG. 23 is a front view thereof;

FIG. 24 is a back view thereof;

FIG. 25 is a left side view thereof;

FIG. 26 is a right side view thereof;

FIG. 27 is a top view thereof; and,

FIG. 28 is a bottom view thereof.

The dot dash broken lines depict the boundaries of the claim and form no part thereof.
